TO STRAUSE GAS IRON CO., OF PHILADELPHIA, PENNSYLVANIA, A CORPORATION
OF PENNSYLVANIA.

BUNSEN BURNER.

1,114,308.

Specification of Letters Patent. Patented Oct. 20, 1914.

Application filed January 3, 1914. Serial No. 810,229.

To all whom it may concern:

Be it known that we, LOUIS J. STRAUSE and OTTO SPAHR, both citizens of the United States, and residents of Philadelphia, county 5 of Philadelphia, State of Pennsylvania, have invented a certain new and useful Improvement in Bunsen Burners, of which the following is a specification.

Our invention relates to what are commonly 10 known as Bunsen burners and more particularly to that type thereof adapted particularly for use in connection with self-heating gas irons and has for its object to provide a superior structure which may be readily 15 adapted for any gas whether natural or manufactured and which may be used to advantage with the gas at any pressure.

Other objects of our improvement will appear from the description hereinafter and 20 the features of novelty will be pointed out in the appended claims.

Reference is to be had to the accompanying drawings in which an example of our invention is shown and in which—

25 Figure 1 is an exterior view thereof; Fig. 2 is a central longitudinal section showing a part of the mixing tube and a part of the usual tube whereby the burner is connected with the source of fuel supply; Fig. 3 is a 30 detail view of the nozzle forming part of our invention; Fig. 4 is a horizontal section on the line 4—4 of Fig. 1; Fig. 5 is a sectional perspective of a connecting or coupling ring included in our construction; Figs. 6 and 7 35 are sectional views of two different forms of our invention and Fig. 8 is a detail view of a substitute tube connection which may be used with Fig. 7.

In the drawings 10 represents the nipple 40 which is adapted to receive the customary flexible or other tube 11 whereby connection with a source of fuel supply is secured and which is provided with a longitudinal passage 12 having its inner end in communication 45 with an enlarged, internally screw-threaded chamber 13. This chamber 13 is adapted to receive the externally screw-threaded neck 14 of the nozzle 15 which is formed with an annular shoulder 16 adapted 50 to engage the end surface of the nipple 10 and limit the inward screwing movement of the neck 14 into the chamber 13 and to thus firmly secure the said nozzle in operative 55 position. In order that the neck 14 of the nozzle 15 may be readily screwed into said

chamber 13, we prefer to provide the free end of said neck with a smooth, slightly reduced unthreaded portion 14^a which enters the chamber 13 first and serves to make the finding of the coöperating threads a simple 60 and easy matter. The said nozzle 15 is provided with a passage 17 and a reduced outlet 18, the two combined forming a continuous channel whereby communication is established between the passage 12 of the nipple 65 10 and the interior of an externally screw-threaded air hood 19, the latter being formed with the customary air inlets 20. This air-hood 19 is made as a separate element from the nipple 10 and is connected 70 therewith by means of a ring or sleeve 21 having an internally screw-threaded portion 22 extending inwardly for a short distance from one end thereof as indicated in Fig. 5. The said screw-threaded portion 22 is adapted 75 for engagement with the screw-threads which extend externally throughout the length of the air-hood 19. At an intermediate point the said sleeve or collar 21 is provided with an internal, annular flange 23 80 adapted to engage a flange 24 of the nipple 10 and rotatable thereon to draw the air-hood 19 against the end surface thereof to firmly secure or couple said hood and nipple together. In the preferred form the internal 85 flange 23 is screw-threaded for engagement with a screw-threaded portion 25 of the nipple 10 for the purpose to be described hereinafter. If desired the sleeve or ring 21 may be provided with one or more knurled or 90 otherwise roughened portions 21^a to provide for a ready manipulation thereof. In order that the amount of air which is admitted to the interior of the air-hood 19 may be regulated as desired, we provide the shutter or 95 ring 26 which is in screw-threaded engagement with the outer surface of said air-hood and may in consequence be manipulated thereon to cover or uncover the air inlets 20 more or less to regulate the intake of air. 100 In the preferred form the ring or shutter 26 is partly slotted or completely split as indicated at 26^a and is initially connected with the hood under a tension, so as to be securely held in any adjusted position thereon and 105 also to accommodate itself automatically to any changes in the threads due to wear or other causes. With this construction a very minute and fine adjustment of the shutter relatively to the air inlets is possible and the 110

coöperating screw threads on the air hood and shutter serve to positively maintain said shutter in any adjusted position. This ring or shutter 26 may also be provided with knurled or otherwise roughened portions 26^b whereby a ready manipulation thereof is made possible. The said air-hood in the example shown is screw-threaded for connection with the customary mixing tube 27.

10 In constructions of the kind to which the present invention relates it is oftentimes necessary to substitute nozzles 15 having outlets or channels differently proportioned for different purposes such as for use with gas under different pressures or for use either with manufactured or natural gas. Under such conditions it will readily be apparent that once the proper nozzle has been incorporated in the structure it is essential that the same be not readily interfered with or tampered with and to protect it against undesired manipulation. With the present construction it will be seen that when the parts are completely assembled the said nozzle 15 is adequately protected by the air hood 19, which extends beyond the same. If this air-hood 19 should be disconnected for any purpose, which may be accomplished either by rotating the sleeve or ring 21 on the nipple 10, or by rotating the air-hood 19 in said sleeve 21, the latter in its normal position on the said nipple 10 will project below the end of the same and will thus still protect the said nozzle 15 against undesired manipulation. It will be seen that in said normal position the screw-threads on the flange 23 are below and out of engagement with the threads 25 so that said sleeve or collar 21 is freely rotatable on the nipple 10 as described, the flange 24 preventing a separation of said sleeve 21 from the said nipple in one direction. When ready access to the nozzle 15 is desired for any purpose, the air-hood 19 is first disconnected from the sleeve 21 to free the latter and permit it to be rotated in a direction to operatively connect said sleeve 21 with the threads 25 and cause it to move along the same to a position where its edge or end which normally projects beyond the nipple 10 no longer thus projects and in consequence leaves the nozzle 15 more freely accessible. The exit end of said nozzle 15 is preferably made cone-shaped as shown best in Fig. 3, so that the recessed end of a suitable tool or implement may be placed over the apex of said cone and said tool given a slight blow or succession of blows whereby the diameter of the outlet 18 at its exit end may be easily contracted or reduced to secure a perfect operation with all kinds of fuel gas under all conditions. Similarly, by inserting a tapered tool into the end of the outlet 18 and tapping said tool the exit end of said outlet 18 may 65 be readily spread or enlarged if for any

reason this should become necessary or advantageous. It will readily be apparent that the above could not be as satisfactorily accomplished if the nozzle were, for instance, rectangular and further that with our improved nozzle it is unnecessary to substitute one complete nozzle for another when slightly different outlets are desired. In addition to this by having said nozzle 15 detachably secured in operative position, the same becomes readily interchangeable when necessary and a nozzle of proper size to meet the existing conditions may thus easily be incorporated in the burner. It is therefore only necessary to supply different nozzles to meet varying conditions instead of different complete burners.

The threads 25 on the nipple 10 and the external threads on the air-hood 19 preferably coöperate in such a manner that the danger of accidentally disconnecting the parts through an accidental manipulation thereof is obviated. To still further prevent such accidental dislocation or disconnection the device is so constructed that the end of the tube 11 may be brought into engagement with the one end of the sleeve or collar 21. This tube both by its frictional engagement with said sleeve or collar 21 and because it acts as a stop against movement in one direction lengthwise of the nipple will thus prevent rotation of said sleeve or collar 21. That portion of the said sleeve or collar 21 which in the illustration is above the flange 23 normally covers the threads 25 and thus protects the same against injury.

In the form of our improvement shown in Fig. 6, the nipple 10^a screws directly into the one end of the air hood 19^a and the sleeve 21 has been omitted. By simply unscrewing said nipple 10^a from said air hood 19^a the nozzle 15^a is carried along with said nipple and is exposed and made readily accessible. Otherwise this form of our invention may be the same as the form first described.

In the construction shown in Fig. 7, the nipple 10^b is provided with an externally screw-threaded neck 10^c adapted to screw into a member 10^d having screw threads 25^d corresponding to the threads 25 of Figs. 1 and 2 and detachably carrying a nozzle 15^b similar to the nozzle 15 hereinbefore described. The said member 10^d is also adapted to support a sleeve corresponding to the sleeve 21 and adapted to connect the nipple 10^b with an air hood and to coöperate with the threads 25^a to expose the nozzle 15^b in the same way as in Figs. 1 and 2. In many cases it is undesirable to connect the burner with a source of fuel supply by means of a tube, the one end of which slips over a nipple such as the nipple 10^a owing to the fact that the tube and nipple sometimes become accidentally disconnected. Under such con-

ditions and wherever a more reliable connection is desired, the nipple 10^b is simply unscrewed from the member 10^d after which the screw threaded end 11^a of the tube 11^b 5 may readily be connected therewith, thus securely connecting the burner and the tube 11^b together against accidental disengagement. The form of tube connection shown in Fig. 8 is a well known and standard one, 10 so that it is only necessary to make the neck 10^c of the same standard size as is the end 11^a of the tube 11^b to secure a perfect interchangeability of the parts. When the ordinary slip over connection is desired the nipple 10^c is simply reconnected with the member 10^d. 15

It will thus be seen that all forms of our invention provide structures which may be easily taken apart and connected and in 20 which the vital parts are thoroughly protected against undesired manipulation or tampering and which may be readily adapted to meet all conditions of use.

Various changes in the specific form 25 shown and described may be made within the scope of the claims without departing from the spirit of our invention.

We claim:

1. A Bunsen burner comprising a nipple, 30 a nozzle thereon, an air hood surrounding said nozzle and abutting against the end of said nipple and means for detachably securing said nipple and air hood together.

2. A Bunsen burner comprising a nipple, 35 a nozzle detachably carried thereby, an air hood surrounding said nozzle abutting against the end of said nipple and a collar rotatably mounted on said nipple for detachably securing the air hood thereto.

40 3. A Bunsen burner comprising a nipple, a nozzle detachably carried thereby, an air hood, a coupling ring swiveled on and normally extending beyond said nipple and adapted to connect the air hood thereto and 45 coöperating means on said nipple and coupling ring respectively whereby the latter may be moved back on said nipple to expose said nozzle, whereby the latter may be freely detachable.

45 4. A Bunsen burner comprising a nipple, a flange on said nipple, a nozzle detachably secured to said nipple, an air hood surrounding said nozzle, a coupling ring normally extending beyond said nipple and adapted 50 for connection with said air hood, an internally screw threaded flange on said coupling ring adapted to rotate on the flange of said nipple whereby said coupling ring is swiveled on the latter and screw threads on said 55 nipple adapted to coöperate with said screw threaded internal flange whereby the coupling ring may be moved back on the nipple to expose said nozzle whereby the latter may be freely detached.

55 5. A Bunsen burner comprising a nipple,

a flange on said nipple, a nozzle detachably secured to said nipple, a screw threaded air hood surrounding said nozzle, a coupling ring normally extending beyond said nipple provided with screw threads adapted to engage the screw threads of said air hood for connecting said air hood and nipple together, an internally screw threaded flange on said coupling ring rotatable on the flange of said nipple whereby said coupling ring is 70 swiveled on the latter and screw threads on said nipple adapted to coöperate with said internally screw threaded flange whereby the coupling ring may be moved back on the nipple to expose said nozzle whereby the 75 latter may be freely detached.

6. A Bunsen burner comprising a nipple, a flange on said nipple, a nozzle detachably secured thereto, an externally screw threaded air hood surrounding said nozzle, a 80 coupling ring extending beyond said nipple provided with screw threads adapted to engage the screw threads of said air hood for connecting said air hood and nipple together, an internally screw threaded flange 85 on said coupling ring and screw threads on said nipple adapted to coöperate with said internally screw threaded flange whereby the coupling ring may be moved back on the nipple, said screw threads on said nipple terminating at a distance from the flange thereof whereby an annular recess is formed on said nipple in which said screw-threaded flange is freely rotatable. 90

7. A Bunsen burner comprising a nipple, 100 a nozzle detachably carried thereby, an externally screw threaded air hood provided with air inlets, a flange on said nipple, a coupling ring normally extending beyond said nipple, screw threads in said projecting portion adapted to coöperate with the screw threads of the air hood for securing said air hood and nipple together, an internally screw threaded flange on said ring, 105 adapted to rotate on the flange of said nipple, screw threads on said nipple adapted to be engaged by said internally screw threaded flange whereby said coupling ring may be moved back on the nipple and means coöperating with said air inlets for adjusting the amount of air admitted to the air hood. 110

8. The combination of a tube adapted for connection with a source of fuel supply, a nipple extending into said tube, a nozzle carried thereby, an air hood surrounding said nozzle, a coupling ring normally extending beyond said nipple and adapted to connect said air hood and nipple together and coöperating screw threads on said coupling ring and nipple respectively normally out of engagement with each other and adapted to be brought into coöperating engagement for moving said coupling ring back on the nipple, said tube being arranged 115 120 125 130

to abut against said coupling ring to prevent rotative movement thereof and movement thereof lengthwise of the nipple in one direction.

9. The combination of a nipple, an air hood, movable means for detachably securing said nipple and air hood together and a fuel conducting tube extending over said nipple into engagement with said means, whereby unintentional actuation of the latter is prevented.

10. The combination of a nipple, an air hood or the like, a coupling ring rotatably mounted on said nipple for detachably se-

curing said nipple and air hood or the like together and a fuel conducting tube extending over said nipple into frictional engagement with said coupling ring, whereby unintentional actuation of the latter is prevented.

20 In testimony whereof, we have hereunto set our hands in the presence of two subscribing witnesses.
